UNITED STATES PATENT OFFICE.

WILLIAM L. PROCUNIER, OF CHICAGO, ILLINOIS.

DESIGN FOR A TAP-CHUCK.

47,199.

Specification for Design.

Patented Apr. 6, 1915.

Application filed January 28, 1915. Serial No. 4,956. Term of patent 3½ years.

To all whom it may concern:

Be it known that I, WILLIAM L. PROCUNIER, a citizen of the United States, residing at Chicago, in the county of Cook and State of Illinois, have invented a new, original, and ornamental Design for a Tap-Chuck, of which the following is a specification, reference being had to the accompanying drawings, forming a part thereof.

The drawing is a side elevation of the design embodying this invention.

Copies of this patent may be obtained for five cents each, by addressing the "Commissioner of Patents, Washington, D. C."

I claim:

The ornamental design for a tap chuck, as shown.

In testimony whereof I have hereunto set my hand at Chicago, Illinois, this 25th day of January, 1915.

WILLIAM L. PROCUNIER.
